UNITED STATES PATENT OFFICE.

VERNON JOHN PHILIP CLIFFORD, OF LONDON, ENGLAND.

LIFE GUARD OR OBSTRUCTION REMOVER FOR MOTOR, ROAD, AND OTHER VEHICLES.

Application filed October 3, 1927, Serial No. 223,810, and in Great Britain October 12, 1926.

This invention refers to improvements in lifeguards or obstruction-removers for motor, road, and other vehicles, and has for its object to provide a device of improved and simplified construction and which will be more certain and effective in operation than devices heretofore provided.

In carrying the present invention into effect, a cushioned and resiliently mounted roller, which may be in one or more lengths or sections, is arranged in front of the front wheels of the vehicle in a fixed or an adjustably mounted frame so that it is normally well clear of, say about eight inches above the surface of the road.

The roller which may be disposed transversely of the vehicle or slightly inclined is so geared or arranged that when in operation it will be lowered into close proximity, or contact, with the ground and will be automatically revolved in an opposite direction to that of the road wheels of the vehicle thereby not only pushing a person or object before it but at the same time turning same over and over thus preventing same from getting under the road wheels.

The roller may be lowered as by hand at the will of the driver by means of suitable mechanism or it may be automatically actuated as by the roller itself, or a trigger mechanism arranged above or in front of said roller, coming into contact with a person or the object on the road.

In order that the present invention may be clearly understood and more readily carried into effect it is hereinafter described by way of example with reference to the accompanying drawings in which:—

Fig. 1 is a sectional side elevation of a rotatable life guard or obstruction remover mounted in front of the steering wheels of a motor road vehicle and adapted to be rotated by means of an electric motor of the type commonly used for starting cars.

Fig. 2 is a similar view to that shown in the preceding figure but showing the device lowered into its operative position just above the surface of the road; and

Fig. 3 is a front elevation showing one portion of the roller in section.

In the particular construction illustrated the roller 10 is made in four sections mounted to revolve together on a common transverse shaft 11 which is supported by pendants 12. The pendants 12 are fitted with ball bearings 13 for the shaft 11 and are pivotally con-

nected to and themselves pivoted at 14 to side plates 15. The pendants 12 are extended backwards to a position behind the roller 10 where they are joined together by a stiffening member or tube 16 the purpose of which is to ensure the roller moving back in a parallel direction when it meets an obstacle at one end of the said roller.

The side plates 15 which ultimately carry the roller and all of the driving mechanism and accessories are pivotally connected at 17 to brackets 18 bolted or otherwise secured to the chassis 19 of the vehicle. Thus not only can the roller itself turn or move back about the pivots 14 but the whole device can turn or move back and down about the pivots 17. Normally the device is maintained in the inoperative position shown in Fig. 1 by means of a latch plate 20 which is pivotally mounted at 21 and which engages a stud 22 fixed to the motor casing or some other suitable part whilst when the latch plate is tripped, as in the manner hereinafter described, the down or working position of the roller 10 (Fig. 2) is determined by the rubber buffers 23, on the rear or extended arms of the side plates 15, making contact with the underside of the chassis 19 of the vehicle.

The motor 24 is mounted between the two side plates 15 on a pair of transverse rods 29 secured thereto so as to come more or less in the centre line of the vehicle, that is, midway between the wheels of the vehicle and so as to enable the forward end 25 of its driving shaft 26 to extend forwardly and by means of the worm pinion 27 at its end to engage with a worm wheel 28 which is mounted in a central position on the roller shaft 11. The wheel 28 and the pinion 27 are mounted in a closed or weather proof casing 129 in a gap provided between the middle pair of roller sections 10. The motor shaft 25, 26 however, in order to allow for the movement of the roller 10 about its pivot 14 is formed in two main sections 25, 26 which are connected by universal joint 30. The rear section 26 is also formed in two portions 26 and 26^a so as to permit of telescopic movement due to the shortening of the shaft as the roller tends to swing back towards the body of the vehicle.

Normally the roller 10 is prevented from rotating on its shaft 11 by means of a ratchet wheel 31 which is engaged by means of a pawl 34 and before the roller can be operated this pawl 34 has first to be pulled out of gear with said ratchet 31. This releasing operation

- may be effected manually as by a link or rod (not shown) connected to an extension lever 35 secured on a shaft 36 carrying the aforesaid pawl 34 or it may be effected automatically 5 as the roller is moved backwards as when striking an object by means of a forked member 37 which is also connected to the shaft 36 and which engages between a pair of collars 38-39 provided on the forward extension 10 shaft 25 of the motor. The swinging of the roller 10 about its pivot 14 is also utilized to operate a suitable electric switch or contact making device adapted to automatically connect the motor up to the source of E. M. F. when the roller is pushed back towards the body of the vehicle. This may conveniently be effected by providing the rearward extension 15 of one of the pendants 12 with a projecting eye 40 which is adapted to engage a knob 11 on a tumbler or like switch 42. The two sections 26, 26^a of the motor shaft are only permitted a certain degree of telescopic movement which is not quite sufficient to take up all the rearward movement of the 20 roller 10 so that towards the end portion of its rearward movement the motor shaft 25, 26^a causes the armature shaft 26 to slide with its armature in its bearings and by means of its projecting end 43 to engage with the 25 lower end of the trip lever 44 engaging the latch plate 20. The movement of this trip lever 44 causes the said latch plate 20 to be moved forwardly and to release the stud 22 and with it the side plates 15 carrying the 30 roller and the motor 24 so that they are free to swing together about the pivots 17 until the buffer 23 comes into contact with the underside of the vehicle chassis, as shown in Fig. 2.
- 40 In operation when the roller 10 comes into contact with an obstacle offering sufficient resistance to over-come the resistance required to operate the switch 42 the roller will be forced slightly backwards and the movement 45 thus given to the pendants 12 will trip the switch 42 and complete the electrical circuit which starts the motor revolving. This first backward movement of the roller also carries backward the worm casing 129 and 50 all its contents, the movement conveniently being one of a magnitude of about $\frac{1}{2}$ ". This movement is compensated for by the telescopic extension of the worm shaft. When this amount of movement has taken place a shoulder 45 on the shaft 26^a strikes a shoulder 46 on the armature shaft 26. Suitable stops (not shown) are also provided in connection with the pendants 12 to take any thrust after this initial movement has taken 55 place. During this time the pawl 34 will be in engagement with the ratchet wheel 31 thereby restraining its movement. As, therefore, the worm wheel 28 cannot revolve the worm pinion 27 will feed its way towards the motor 24 and as the telescopic shaft 26 and 26^a

has previously been closed up the rearward movement of the worm will be imparted to the armature. This rearward movement of the worm pinion 27 will also cause the shoulder 39 to engage the lever 37 and so withdraw the pawl 34 from the ratchet wheel 31. The movement of the armature due to the rotation of the worm will also operate the rocking lever 44 sufficiently to cause the latch plate 20 to become disengaged from the stud 22. At this point the roller 10 begins to fall about its pivots 17 until it assumes the position shown in Figure 2 of the drawings when the buffer 23 is up into close contact with the inside of the chassis frame 19. The roller will then be revolving in an anticlockwise direction which will be found to effectively prevent any person or object encountered from passing under the roller to the road wheels of the vehicle. Conveniently the peripheral speed of the roller may be equal to or greater than the speed of the car with respect to the road surface so that the roller which may as shown also have a roughened or longitudinally ribbed surface will always exert a lifting effect upon anybody or anything coming in contact with it. In the particular construction illustrated the roller may be formed of aluminum in order to reduce the weight and resistance to movement when starting. It may comprise a central tubular shaft 11 and discs or flanges carrying the outer tubular casing on which are arranged spaced longitudinal ribs 146.

The safety roller may be formed of or be covered with solid rubber or it may be provided with a pneumatic cushion or cushions, thus the roller may also serve as a buffer to minimize damage by collision. This buffer effect may also be obtained or augmented by the introduction of suitable springs or air or hydraulic shock absorbers, in connection with an adjustably mounted roller carrying frame.

The improved device may be applied to the rear wheels of a vehicle also and a net may also be used in conjunction with the roller if desired so as to catch the person or other object when same is lifted up or falls over the rollers.

In a modified construction, the arrangement of the roller 10 in its frame 15 may be such that when the roller and frame are lowered a small auxiliary road wheel on the frame which is normally in frictional contact with the safety roller will make contact with the road and will drive the said safety roller 10 in the opposite direction. Alternatively the safety roller 10 may be driven from the vehicle as by means of a flexible shaft from the mechanism of the car or by compressed air. In the latter cases the drive may be controlled by suitable means from the driver's seat. In some cases the motor driving the roller may be arranged within the

roller itself and such an arrangement may be found to be especially convenient in the case of an electric motor or of a motor working by compressed air in which case the roller could form the rotor of the motor.

- 5 The roller or rollers may be so arranged in relation to the steering wheels of the vehicle that when the latter is turned to the right or left the roller or rollers will move in conjunction with the steering wheels in order to guard them. Modified means may also be provided for ensuring that the roller will be given a suitable peripheral speed or momentum before it actually reaches the ground.
- 10 15 This may be done by the provision in conjunction with the trigger release mechanism previously described of a strong clockwork spring or springs which may be arranged within the roller so as to cause it to be rapidly revolved the instant it is released or by the provision of a spring or springs serving to force a toothed wheel on the roller or rollers along a toothed rack or racks as it passes down towards the ground, thus giving the 20 25 roller an initial impulse to assist the driving mechanism.

In some cases also springs may be employed for giving extra pressure to retain the roller or rollers in contact with the ground and if desired such springs may also be those employed for speeding up and giving initial rotation to the roller itself.

- 30 A shield or guard may also be provided in conjunction with the said roller and this 35 would preferably be arranged just above said roller so as to support any person thrown by the roller and to prevent them from getting thrown by the upper portion of the said roller on to the front of the vehicle. In a 40 further slightly modified construction I may employ a plurality of driving wheels for the roller and these wheels may be driven by any suitable gearing from the motor itself or from any other source of power employed.
- 45 The said driving wheels may be mounted on the roller itself or may be geared to the roller in such a manner that the motion is conveyed to the roller or rollers in a reverse direction to that in which the wheels of the vehicle are 50 rotated as previously described.

In some cases the device may be made collapsible, that is to say, where garage space is a consideration of importance the device may be made to hinge or fold up so that when 55 the vehicle is not in use the roller can be turned up into a position above the engine or radiator of the vehicle. Also the roller may comprise a corrugated or other band running over a plurality of rollers as will be 60 readily understood.

What I claim is:—

- 65 1. A life guard or obstruction remover comprising a frame pivotally supported between its ends, a guard member pivotally mounted at the forward end of the frame, a

latch at the rear end of the frame normally holding the forward end of the frame raised, and means for releasing the latch when the guard member strikes an obstruction and is 70 swung downwardly.

2. A life guard or obstruction remover comprising a roller, means for supporting the roller from a vehicle and permitting vertical movement thereof, means for positively rotating the roller, means for normally restraining rotation of the roller, and means operable by the rotating means upon lowering of the roller to release said restraining means and permit rotation of the roller.

75 3. A life guard or obstruction remover comprising a frame, means for pivotally mounting the frame upon a vehicle, a roller, pendants carrying the roller and pivoted upon the front end of the frame, means for normally holding the front end of the frame 80 raised, means for positively rotating the roller, and means whereby downward pivotal movement of the pendants and the roller will release said frame holding means and effect actuation of the rotating means. 90

4. A life guard or obstruction remover comprising a frame, means for pivotally mounting the frame upon a vehicle, a roller carried by the front end of the frame, and a rubber buffer on the frame to limit the 95 downward movement of the front end of the frame.

5. A life guard or obstruction remover comprising a frame, a roller mounted at the front of the frame and consisting of a plurality of axially aligned sections, a motor on the frame having its shaft extending to the roller, a worm on the motor shaft, and a worm wheel fixed to the roller between two of the sections thereof and meshing with 100 said worm.

105 6. A life guard comprising a frame, means for pivotally supporting the frame upon a vehicle, a latch engageable with the rear portion of the frame to normally hold the 110 front end thereof raised, a roller mounted on the front end of the frame for vertical movement relative to the frame, a trip lever mounted on the frame and having one end bearing against the latch, and an element 115 bearing against the opposite end of the trip lever and movable longitudinally of the frame and cooperating with the roller whereby upon downward movement of the roller the latch will be released and the frame permitted to rock downwardly at its front end. 120

7. A life guard comprising a frame, a roller pivotally mounted on the frame, a worm wheel fixed to the roller on the axis thereof, a ratchet fixed concentrically to the 125 worm wheel, a pawl mounted on the frame and engaging said ratchet, a shaft mounted in the frame for endwise movement, a worm on said shaft meshing with the worm wheel, means for rotating the shaft rendered 130

operative by downward movement of the roller, an element depending from the pawl, and a collar on the shaft to engage said element whereby to release the pawl from the ratchet and permit rotation of the roller.

8. A life guard comprising a vertically swinging frame, latch mechanism at the rear end of the frame normally holding the front end thereof raised, a roller mounted at the front end of the frame for relative vertical swinging movement, an electric motor on the frame, an endwise movable armature shaft for the motor extending longitudinally of the frame and comprising a front section adjacent the roller, an intermediate section connected with the front sec-

tion by a universal joint and a rear section telescopically connected with the intermediate section and having its rear end engaging the latch mechanism, means actuated by downward movement of the roller to close the motor circuit, means for rotating the roller including a worm wheel fixed to the roller and a worm on the front section of the armature shaft meshing with the worm wheel, means cooperating with the worm wheel to restrain rotation of the same, and means on the front section of the armature shaft to release said restraining means.

In testimony whereof I have hereunto signed my name.

VERNON JOHN PHILIP CLIFFORD.
